UNITED STATES PATENT OFFICE.

MAXIMILIAN J. KOENIG, OF JERSEY SHORE, PENNSYLVANIA.

INVALID-CHAIR.

SPECIFICATION forming part of Letters Patent No. 276,429, dated April 24, 1883.

Application filed September 12, 1882. (Model.)

To all whom it may concern:

Be it known that I, MAXIMILIAN JOSEPH KOENIG, of Jersey Shore, in the county of Lycoming and State of Pennsylvania, have invented a new and Improved Invalid-Chair, of which the following is a full, clear, and exact description.

The object of my invention is to provide new and improved attachments for chairs, which, when attached to a chair, convert the same into an invalid-chair which can easily be moved about.

The invention consists in the combination, with an ordinary chair, of detachable wheels, whereby the chair can easily be converted into an invalid-chair.

The invention further consists in journal-boxes attached to the under side of the chair, and in wheels provided with axle-sections which pass through the journal-boxes and into the ends of a removable journal-box held under the seat.

The invention further consists in a rear wheel journaled in a removable vertical shaft.

The invention also consists in the combination, with the axle-sections and shaft, of adjustable collars for holding the wheels in place.

Reference is to be had to the accompanying drawings, forming a part of this specification, in which similar letters of reference indicate corresponding parts in all the figures.

Figure 1 is a partly sectional side elevation of a rocking-chair provided with my improved attachments on the line xx , Fig. 2. Fig. 2 is a front elevation of the same, parts being broken away and others shown in section. Fig. 3 is a plan view of the slotted coupling-bar.

Journal-boxes A are attached to the bottom of a chair, B, near the front, and at the sides wheels C are provided, with fixed axle-sections D, which are passed through the journal-boxes A, and into the opposite ends of a tubular journal-box, E, held transversely under the chair-seat, at the end of a longitudinal bar, F, attached to a downwardly-projecting bracket-frame, G, attached to the bottom of the chair-seat at the rear end of the same. The front end of the bar F is slotted longitudinally, and a thumb-screw, G', passes through the slot into a projection, E', of the tubular journal-box E. By this construction the bar F and the projection E' of the tubular bearing E are adjustably

secured together, thereby permitting the wheels C and caster-wheel H to be coupled closer together or farther apart to suit different sizes of chairs.

A wheel, H, is journaled on the lower forked end, H', of a vertical shaft, J, which is swiveled or held to turn on its longitudinal axis in bearings at the rear end of the bar F. By means of a collar, K, provided with a binding-screw, K', the shaft J can be so adjusted that the rear end of the bar F will be a greater or less distance from the lower end of the said shaft. Collars L, provided with binding-screws L', are loosely mounted on the axle-sections D. The axle-sections are passed through the journal-boxes A and into the ends of the journal-box E, and are held in place by the collars L, one of which is placed against each side of a journal-box A, and is held in place by its screw L'. The wheels C must be of such diameter that when the same are attached to the chair B the rockers M of the same will be raised from the floor, as shown. The shaft J can be so adjusted that the chair can be inclined backward more or less, as may be desired. The wheels C and H can easily be attached to and removed from any chair of any width, and thus a rocking-chair of any kind can easily be converted into an invalid-chair in a very short time, and if it is to be used as a rocking-chair again the wheels can be removed just as rapidly.

The wheels, journal-boxes, &c., can be fitted to a chair of any width. The bar F and the journal-boxes A are the only parts that must be screwed, pivoted, or otherwise fixed to a chair. An invalid-chair can thus be made out of an ordinary chair at a very small expense.

I am aware that axle-sections revolving with the wheels have heretofore been employed; and I am also aware that axle-sections have been secured in a sleeve by means of screws passing through said sleeve and working in grooves of said axle-sections; and I am further aware that the shank of a collar has been secured in a socket-clamp by a collar and set-screw on said shank, and I therefore do not claim such inventions.

Having thus fully described my invention, I claim as new and desire to secure by Letters Patent—

1. In an attachment for chairs, the combination, with the journal-boxes A and the wheels

C, each provided with a fixed axle-section, D, of the tubular journal-box E, for receiving the ends of the axle-sections, substantially as herein shown and described.

5 2. In an attachment for chairs, the combination, with the journal-boxes A and the wheels C, provided with fixed axle-sections D, of the adjustable collars L and the tubular journal-box E, substantially as herein shown and described, whereby the wheels can be adjusted to or from each other, as and for the purpose set forth.

10 3. In an attachment for chairs, the combination, with the journal-boxes A and the wheels C, provided with fixed axle-sections D, of the 15 collars L, adjustably secured to the axle-sections on each side of the journal-boxes, the tubular journal-box E, the bar F, adjustably secured to the tubular bearing E, the bracket-frame G, and the caster-wheel H J, substan-

tially as herein shown and described, whereby 20 the attachment can be attached to chairs of different sizes, as set forth.

4. In an attachment for chairs, the combination, with the axle-box A, the tubular bearing E, provided with the extension E', and the 25 wheels C, provided with axle-sections, D adjustably secured in said bearings, of the slotted bar F, the thumb-screw G', the bracket-frame G, and the caster-wheel H J, substantially as herein shown and described, whereby 30 the wheels can be adjusted to or from each other, and the said wheels and caster-wheel coupled closer together or farther apart, as and for the purpose set forth.

MAXIMILIAN JOSEPH KOENIG.
